UNITED STATES PATENT OFFICE.

ANDREW M. PLATT, OF NEW HAVEN, CONNECTICUT.

SHIPPING-CASE.

SPECIFICATION forming part of Letters Patent No. 293,513, dated February 12, 1884.

Application filed December 4, 1883. (No model.)

To all whom it may concern:

Be it known that I, ANDREW M. PLATT, a citizen of the United States, residing at New Haven, in the county of New Haven and State 5 of Connecticut, have invented a new and useful Shipping-Case, of which the following is a specification, reference being had to the accompanying drawings.

This invention relates to shipping-cases, and especially to that class of the same which are adapted to fold up; and it has for its object to provide means whereby the folding sections will be held together in a safe and secure manner, and may be folded into a very small space 15 when it is desired to return the case to the owner.

With these objects in view the said invention consists in securing the sides together by spring catches or locks, and in hinging the 20 several sections in such a manner as to allow folding of the same one upon the other in the smallest space possible, and in certain details of construction and combination of parts, as hereinafter set forth, and particularly pointed 25 out in the claims.

In the accompanying drawings, Figure 1 is a perspective view of my improved shipping-case in its closed position. Fig. 2 is a similar view, a portion of the case being open to show 30 the manner in which the case is unpacked. Fig. 3 is a view of the case in its closed position, ready to be returned to its owner. Fig. 4 is a detail view, showing the operation of the spring-catch. Fig. 5 is a sectional view.

Like letters of reference indicate corresponding parts in the several figures.

Referring to the drawings, A is the bottom of my improved shipping-case, having cross-pieces *a* secured to the under side thereof at 40 each end, the ends B B' of the case being hinged to the upper face of the bottom, so as to be capable of folding flat against the same. Vertical strips *b* *b'* are secured to the outer face of the ends B B' on each side, the strips *b* of the end B extending upward beyond the same and connected by a cross-bar, C, said cross-bar and the extended ends of the strips *b* fitting within a cut-away portion, *c*, of the strips *b'*, flat against the end B', when the case 50 is folded.

D D' designate the sides of the case, having

vertical strips *d* *d'* secured to and extending up along the same on their opposite ends. Hinges *e* connect the strips *d* of the side D to the cross-pieces *a* of the bottom, the adjacent 55 ends of the strips *d* and the cross-pieces being beveled or chamfered, as at *f*, to permit a tight fit when the parts are connected to form the box or case. The side D' is hinged directly to a cleat, *g*, secured to the bottom A, so as to 60 allow the said side to fold over the ends B B', the other side folding against the under side of the bottom.

E designates the cover or top piece, comprising two sections or parts, *h* *h'*, provided with cross-pieces *i* *i'* on each end, the section or part *h* being hinged directly to the side D, so as to fold against the inner face of the same, while the cross-pieces *i'* of the other section or part, *h'*, are extended, as at *j*, and hinged at 70 the extensions to the strips *d'* of the side D', thus permitting the said section *h'* to fold flat against the exterior face of the side D'.

In securing the sides and ends of my improved case together I use improved catches 75 or locks, the construction of which is as follows: Rods F project from the sides of the ends B B', and are provided with beveled catches *k*, which extend or work through sockets *l* in the ends of sides D D'. To one side of the 80 sockets *l* are pivoted levers G, which engage at their front ends with the catches *k*, projecting through the sockets *l*, said levers being provided with a bearing-piece, H, near their center. Above the levers are projections I of 85 the sides D D', coiled springs J being secured at one end to a lug, *m*, depending from the projections, and at the other end to a lug, *n*, projecting from the upper end of the bearing-piece H. To the inner face of the levers G 90 are secured headed studs K, which work in elongated slots L in the sides D D', operating-rod M being secured to the heads of the studs K and working vertically in guides O, attached to the interior face of the sides. 95

From the foregoing description the operation of the locks or catches will be readily understood. By catching hold of the upper end of the rod M and drawing the same upward, the lever is disengaged from the catch *k* and the spring J is compressed, and when the rod M is released the spring exerts its power and 100

causes the return of the lever to its normal position. By means of this construction the levers will always be in position to be operated by the insertion of catches *h* through sockets *L*, the levers fitting partly over the sockets and adapted to move aside in an upward direction through the yielding of springs *J*.

It will be seen that each corner of the case is provided with the spring catches or locks, 10 the rods *F*, with the beveled catches, projecting from the ends *B B'*, while the locking-levers are attached to the sides *D D'*, all portions of the locking mechanism being concealed from view by suitable inclosing-frames, *Z*, attached to the upper corners of the sides, and recessed to permit the free movement of the spring-pressed lever. Headed screws or screw-eyes *N* attach the lid or cover sections in place and work through suitable metallic sockets, *o*, 20 in the sections *h h'* and the ends *B B'*, said screw or screw-eyes being readily detached when it is desired to unpack the contents of the case.

In place of the screws or screw-eyes, I may 25 use pivoted hooks, which may be attached to the ends *B B'*, and catch at their ends through screw-eyes secured to the lid or cover sections.

It will be apparent that I may also use the spring catches or locks to hold the cover in 30 place, thus employing eight locks for each case, the operation and functions of all the catches or locks being the same.

The operation of my invention can be readily understood from the foregoing description, 35 taken in connection with the annexed drawings. When the shipping-case containing the merchandise has reached its destination, the section or part *h* of the cover is released by withdrawing the screws or other fastenings 40 for the same, and the spring catches or locks on each end of the side *D* are released, so as to allow said side to drop down in the position shown in Fig. 2, when the contents of the case can be readily taken out, as desired. If it is 45 desired to return the shipping-case to the owner, as is generally the case, the other section of the cover is permitted to drop down against the outer face of side *D'*, the spring catches or locks of said side being released, 50 thus allowing the ends *B B'* to fold flat against the upper face of the bottom *A*, one of the sides, *D'*, folding over the ends *B B'*, while the other side, *D*, folds against the under side of the bottom, each side carrying a section of the 55 cover, as shown. To the under side of the section *h* of the cover are attached straps *N*, which, when the sections of the case are folded together in the position shown in Fig. 3, will engage or connect with projections or studs *p*, 60 secured to the other section of the cover. Thus the parts will be held securely together in their folded position, and there will be no danger of separating the same when it is desired to return the folded case to the owner. 65 If it should be desired to use the case again for the shipment of merchandise, the side *D'*

is raised, together with the ends *B B'*, the spring-locks at the corners automatically holding the parts in upright position. A certain quantity of the merchandise may be placed in 70 the case, one of the sides being open for that purpose, and then the other side, *D*, is locked in place, the remainder of the case being filled to the desired height, the sections of the cover or lid being secured in place by the means before stated. When locked in this position, the case will be held firmly together at all corners, and there will be no possible danger of the sections separating for any cause whatever.

The advantages of my invention are obvious. 80 By means of the improved shipping-case shown, the merchandise contained therein may be easily removed, since there will be no necessity of using force to separate the case, such as is used in separating the common boxes 85 ordinarily employed in shipping merchandise. When the entire contents of the case have been removed, the case can be folded into the position shown in Fig. 3 and forwarded back to the owner, a label-holder, *P*, being secured to 90 both the inner and outer faces of the section *h* of the cover, in which suitable cards or labels containing the names and addresses of the receiver and consignor of the case are placed, to be used in forwarding and returning the 95 said case. When the shipping-case is properly constructed, it will be much stronger than the ordinary nailed case, and can be used until worn out. A large shipping-house, using, 100 say, twelve hundred cases a year, could transact their business with one hundred of my cases, thereby saving the cost and storage of eleven hundred cases. When the case is folded together, it occupies a very small space, and may be packed together in piles until used.

Other advantages of my invention are apparent, and need not be particularly pointed out here.

Having thus described my invention, I claim as new—

1. In a shipping-case, the ends folded flat against the bottom, and the sides each carrying a section of the cover, one of the sides extending over the folded ends, while the other folds flat against the underside of the bottom, 115 as and for the purpose set forth.

2. In a shipping-case, the ends hinged to the upper face of the bottom, and the sides each carrying a section of the cover, one of the sides being hinged to the bottom in such a 120 manner as to fold against the underside of the same, and the other side being hinged to a cleat extending up from the bottom, so as to fold over the ends, the two sections of the cover folding over the sides, and the parts being secured in this position by means of suitable straps, as and for the purpose set forth.

3. In a shipping-case, the ends hinged to the upper face of the bottom and folding flat against the same, one of the ends being provided with a cross-bar overlapping the other 130 end, and the bottom having cross-pieces se-

cured to its under side, in combination with the sides provided with vertical strips, one of the sides being hinged to a cleat projecting up from the bottom, and the other side having 5 hinges connecting its vertical strips to the cross-pieces of the bottom, and the cover or lid formed in two sections or parts, one section being hinged to each side, so as to fold flat against the inner and outer faces of the 10 same, as and for the purpose set forth.

4. In a shipping-case, the sides and ends hinged to the bottom in any suitable manner, beveled catches or rods projecting from the 15 ends and extending through openings or sockets in the sides, and a spring-pressed lever engaging with the catch and arranged to hold the parts in place, as and for the purpose set forth.

5. In a shipping-case, the sides and ends 20 hinged to the bottom in any suitable manner, beveled catches or rods projecting from the ends and extending through openings or sockets in the sides, and a spring-pressed lever engaging with the catch and provided with an 25 operating-rod, as and for the purpose set forth.

6. In a shipping-case, the sides and ends

hinged to the bottom in any suitable manner, beveled catches or rods projecting from the 30 ends and extending through openings or sockets in the sides, a spring-pressed lever engaging with the catch, a rod or projection attached to the lever and working in a slot in the sides of the case, and a rod attached to the head of said projection and working in guides on the interior of the said sides, as and for the 35 purpose set forth.

7. In a shipping-case, the ends folding flat against the bottom, and the sides carrying a section of the cover, one of the sides extending over the said ends, and the other side folding flat against the under side of the bottom, beveled catches projecting from the ends, and 40 spring-pressed levers engaging with said catches, as and for the purposes set forth.

In testimony that I claim the foregoing as 45 my own I have hereto affixed my signature in presence of two witnesses.

ANDREW M. PLATT.
